UNITED STATES PATENT OFFICE.

ISIDOR DEUTSCH, OF MONTREAL, QUEBEC, CANADA, ASSIGNOR TO
ELECTRIC AND TRAIN LIGHTING SYNDICATE, LIMITED, OF MON-
TREAL, CANADA, A CORPORATION OF CANADA.

FLEXIBLE SUPPORT FOR MACHINES MOUNTED ON AN AXLE.

No. 839,735.

Specification of Letters Patent.

Patented Dec. 25, 1906.

Application filed February 16, 1906. Serial No. 301,433.

To all whom it may concern:

Be it known that I, ISIDOR DEUTSCH, a citizen of the United States of America, residing at 112 St. James street, in the city and district of Montreal, in the Province of Quebec, in the Dominion of Canada, have invented certain new and useful Improvements in Flexible Supports for Machines Mounted on an Axle, of which the following is a specification.

The invention relates to improvements in flexible supports for machines mounted on an axle, as described in the present specification and illustrated by the accompanying drawings, that form part of the same.

The invention consists, essentially, of a rotatable axle, a machine mounted thereon, a rigid member independent of said axle, a subsidiary rigid member independent of said axle, means connecting said machine with said rigid member, and a member pivotally secured to said machine and connecting said subsidiary rigid member thereto.

The objects of the invention are to devise a means of supporting a machine on a rotating axle, in which the varying positions of a frame and an axle in relation one to the other shall be accommodated without jarring the machine, and to provide in such devices compensating features whereby the stress on one group of parts is relieved by another group of parts, thus obtaining durability and to secure resiliency in operation.

In the drawings, Figure 1 is a perspective view of the invention applied to a power-transmission device mounted on an axle journaled in a vehicle-truck. Fig. 2 is an enlarged view showing a front elevation of the device and portion of the truck-frame in cross-section.

Referring to the drawings, *a* is the axle, here shown as forming part of the running-gear on a railway-car.

b designates beams forming part of the truck-frame.

c is a bar secured at each end to a beam *b* and preferably arranged in alinement with the axle. The bar *c* forms the fixed support for the transmitting device mounted on the axle *d* therebelow and has the central slot *d* substantially oval-shaped.

e is a casing having the offset portion *f* and

containing a driving mechanism which communicates a rotatory motion to the shaft *g*.

It must be understood that in this brief description of the transmitting device I do not wish to confine myself to any one type of machine and that without departing from the spirit of my invention it may be applied to any form of machine mounted on a rotating shaft and requiring flexible connection with a fixed support.

h is an upright stud fixedly secured to the top of the transmission-casing *e* and encircled for the greater part of its length by a removable sleeve *i*. *j* is a hole through the stud *h* in proximity to the top thereof and immediately above the washer *k*.

l is a cotter-pin inserted through the hole *j* and locking the said washer and sleeve on the stud *h*. The stud *h*, encircled by the sleeve *i*, extends upwardly through the slot *d* in the fixed supporting-bar *c*.

m is a shoe mounted on the upper projecting end of the stud *h* on the sleeve *i* and resting on the fixed supporting-bar *c* and having the lugs *n* projecting downwardly below the bar *c*.

o designates bolts securing the bars *5* to the bottom of the lugs *n* beneath the bar *c*.

It will be thus seen that the retaining-support for the transmission-casing is provided in the stud *h*, projecting through the fixed bar *c*, and all movements of the axle in its bearings are accommodated by the movement of the stud *h* in the slot *d*. *p* designates subsidiary hanger-bars bolted to the bar *c* and rigid therewith and extending laterally therefrom and having the holes *q* and *r* therethrough toward their outer ends.

s is an ear from the offset portion *f* of the casing *e*, and *t* is a link pivoted on the lug *s* and pivotally secured at its upper end to the yoke *u*. The yoke *u* extends to each side of said link in a downward direction and at its extremities has the slots *v*.

w designates eyebolts having the rings *x* encircling the bars *p* between the holes *q* and *r*.

y designates cotter-pins inserted through the holes *q* and *r* at each end of the rings *x* and retaining said rings on the rods *p*.

z designates washers between said cotter-pins and said rings.

The eyebolts *w* extend through the slots *v* of the yoke *u* and at their lower ends have the washers *2* and nuts *3* secured thereon.

4 designates spiral springs encircling the 5 eyebolts *w* between the yoke *u* and the washers *z*, the said washers and the said yoke forming the stops for said spring at each end thereof. This arrangement of yoke, spring, and eyebolts connected with the subsidiary 10 supporting-bars *p* forms a means of constantly returning the stud *h* to its normal position in the slot, and in any change of position caused by the varying movements of the axle of a vehicle in travel the jarring and 15 jolting on the machine supported will be reduced to a minimum.

The utility of a device of the class described is well known in supporting transmission devices in vehicles and in supporting 20 motors and dynamos on rotating axles. In supporting motors and dynamos it is essential to have a device which will ease off the effect of a sudden jump of the axle when adjustably journaled, as is the case in railway- 25 cars.

The wear and tear on a machine mounted on an axle is a serious drawback where the jar is not properly accounted for, and in the present invention it will be readily seen from the 30 description that the yoke acts as an equalizer in any sudden shock by the tilting of the axle and prevents that shock from reaching the parts of the machine to any serious extent and in addition relieves the strain on the 35 main supporting-stud, and this is particularly essential when the lubrication has been neglected and the pull on the stud abnormal.

The sleeve on the main supporting-stud will render the repair to the stud very simple, 40 as the sleeve may be replaced from time to time instead of removing the casing in order to renew the stud.

The portion of the supporting-stud is herein described as upright, with the fixed supporting-bar directly over the machine; but it must be understood that the casing may be supported in any position suitable to the needs of the occasion and the fixed supporting-bar arranged accordingly. This arrangement of yoke-spring and eyebolts connected with the subsidiary supporting-bar *p* forms a means of relieving the stud *h* of the weight of the shaft, and in any change of position caused by the varying movements of the 55 axle of a vehicle in travel the shock on the machine supported will be reduced to a minimum.

The weight of the shaft and the hammer-blow delivered to the stud *h* as a consequence 60 of this weight when a moving vehicle passes over inequalities in the road—for instance, a car-truck passing over switches, frogs, or loose joints in the track, together with the continuous axle play—causes considerable 65 wear in the stud *h* unless some provision is

made to take the unbalanced weight and shock, as explained.

If the stud *h* is permitted to wear to any extent, the angularity of the universal joints is increased, the effect of sudden shock is 70 emphasized by reason of the extra motion between parts of the transmission itself, due to wear on retaining-surfaces, and as a consequence the life of the transmission is materially shortened. 75

It is required, however, that the transmission-support shall not in any way interfere with the relative motion between vehicle frame and axle and shall be unaffected by the application of brakes, wear in axle-boxes, 80 and shall offer no obstacle to the speedy changing of wheels.

What I claim as my invention is—

1. In a device of the class described, the combination with a rotatable axle, a casing 85 mounted thereon and a rigid supporting member independent of said axle, of a subsidiary rigid supporting member independent of said axle, means connecting the aforesaid rigid member with said casing, and a 90 member pivotally secured to said casing and connecting said subsidiary rigid members thereto, as and for the purpose specified.

2. In a device of the class described, the combination with a rotatable axle, a member 95 mounted thereon and a main rigid supporting member independent of said axle, of subsidiary supporting members rigid with the said main rigid member and extending therefrom, means connecting said casing with said 100 main rigid member, and a member pivotally connected to said casing and connecting said subsidiary members thereto, as and for the purpose specified.

3. In a device of the class described, the combination with a rotatable axle, a member mounted thereon and a main rigid supporting member independent of said axle and having a central slot therein, of subsidiary 110 rigid supporting members extending laterally from said main rigid member to each side of said slot, a stud extending from said 115 machine through said slot, and a member pivotally connected to said machine and with said subsidiary rigid members, as and for the purpose specified.

4. In a device of the class described, in combination, a rotatable axle, a machine mounted thereon, a frame in which said axle is journaled, a supporting-bar rigid with said 120 frame and having a central slot therethrough, a stud rigid with said machine and extending therefrom through said slot, subsidiary supporting-bars rigid with the aforesaid supporting-bar and extending laterally therefrom at each side of said slot, and a yoke pivotally connected to said machine and to said 125 subsidiary bars, as and for the purpose specified.

5. In a device of the class described, in 130

combination, a rotatable axle, a machine mounted thereon, a frame in which said axle is journaled, a fixed supporting-bar secured to said frame immediately above said axle and having an oval-shaped central slot, a stud fixedly secured to said machine and extending through said oval-shaped slot, subsidiary supporting-bars extending laterally from said fixed supporting-bar and rigid therewith, a yoke linked to said machine and terminating in suitable eyeholes, eyebolts extending downwardly through said eyeholes from said subsidiary supporting-bars, and having nuts secured at their lower ends, and spiral springs encircling said eyebolts between said yoke and said nuts, as and for the purpose specified.

6. In a device of the class described, in combination, a rotatable axle, a machine mounted thereon, a frame in which said axle is journaled, a fixed supporting-bar secured to said frame above said axle and having an

oval-shaped central slot, a stud fixedly secured to said casing and extending through said oval-shaped slot, a link pivoted to a lug 25 on said machine, a yoke pivotally secured to the upper end of said link and extending to each side thereof in a downward direction having eyeholes at the extremities thereof, subsidiary supporting-bars rigid with said 30 fixed supporting-bar and extending laterally therefrom, eyebolts secured on the said subsidiary supporting-bars and extending downwardly through said eyeholes in the yoke and having at their lower ends suitable 35 nuts, and spiral springs encircling said eye portion between said yoke and said nuts, as and for the purpose specified.

Signed at Montreal this 12th day of February, 1906.
